UNITED STATES PATENT OFFICE.

BENJAMIN SCHARDT, OF DAYTON, OHIO, ASSIGNOR OF ONE-HALF TO JOHN R. FLETCHER, OF SAME PLACE.

FASTENER FOR COG-WHEEL KEYS.

SPECIFICATION forming part of Letters Patent No. 392,972, dated November 13, 1888.

Application filed February 20, 1888. Serial No. 264,604. (No model.)

To all whom it may concern:

Be it known that I, BENJAMIN SCHARDT, a citizen of the United States, residing at Dayton, in the county of Montgomery and State of Ohio, 5 have invented a certain new and useful Improvement in Fasteners for Cog-Wheel Keys; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

15 My invention relates to an improvement in fasteners for cog-wheel keys; and it consists of the ordinary wooden key provided with a transverse notch in its under side, in which is held a curved metallic spring whose edges engage the sides of the cogs as it is being driven home, and from which the said key cannot be withdrawn, as the edges engage the cogs by indentation, and thereby the key is firmly held in position.

20 The mechanism is illustrated in the accompanying drawings, in which—

Figure 1 is a side view of a cog-wheel in which but three cogs are shown. Fig. 2 is a section of two cogs on a line of the inner surface of the rim of the cog-wheel and the inner surface of the wooden key, with a curved spring in a notch of the same. Fig. 3 is a side view of the said key. Fig. 4 is two views of the metallic fastener.

25 Like letters designate like parts throughout the several views.

A is an ordinary cast-iron wheel, which has apertures throughout its periphery to receive wooden cogs. Three cogs are shown at b, Fig. 1, and the two wooden keys c are used to bind

the said cogs within the wheel. These parts are constructed as usual, the cogs and keys having the proper bevel, so that the driving home of the key firmly binds the cogs within the rim. Within the inner surface of the wooden key is formed the notch e, Figs. 2 and 3. This notch binds the body of the metallic spring d at its center and admits of the ends being bent inward as the key is being driven home between the two cogs. Any attempt to drive 45 the key from its seat would cause the points of the spring to indent the cogs so fully that a withdrawal would be impossible. With this construction the fastening of the cogs is complete and the jar and attrition of the moving 50 wheels would fail to detach the cogs, as is frequently the case as the cogs are ordinarily secured. While the object of this invention is to securely fasten keys driven to secure cogs in position, there may be many other uses to 55 which the device is adapted.

Having fully described my invention, what I claim, and desire to secure by Letters Patent, is—

A means for securing wooden cogs in a 60 wheel-rim, consisting of a key adapted to be inserted between two of such teeth, the key being transversely grooved, and a curved metallic spring fitting in said groove, and having its ends adapted to bite into the adjacent cogs 65 when the key is forced between them, and thus prevent their withdrawal, substantially as described.

In testimony that I claim the foregoing as my own I affix my signature in presence of two witnesses.

BENJAMIN SCHARDT.
